DESIGN FOR A RUG

Richard F. Bemporad, New York, N. Y., assignor to Atlantic Rug Co., Inc., New York, N. Y., a corporation of New York

Application November 11, 1937, Serial No. 72,797

Term of patent 7 years

To all whom it may concern:

Be it known that I, Richard F. Bemporad, a subject of the Kingdom of Italy and a resident of 118 Madison Avenue, New York, New York, have invented a new, original, and ornamental Design for Rugs, of which the following is a specification, reference being had to the accompanying drawing, forming part thereof.

The figure is a plan view of a rug, showing my new design.

I claim:
The ornamental design for a rug, as shown.

RICHARD F. BEMPORAD.
